UNITED STATES PATENT OFFICE.

LINCOLN H. BARTLETT, OF CHICAGO, ILLINOIS, ASSIGNOR OF ONE-HALF TO
CHARLES R. HARSHBERGER, OF SAME PLACE.

NECKSCARF.

SPECIFICATION forming part of Letters Patent No. 460,259, dated September 29, 1891.

Application filed January 21, 1890. Serial No. 337,650. (No model.)

To all whom it may concern:

Be it known that I, LINCOLN H. BARTLETT, of Chicago, in the county of Cook and State of Illinois, have invented certain new and useful Improvements in Scarfs; and I do hereby declare that the following is a full, clear, and exact description thereof, reference being had to the accompanying drawings, and to the letters of reference marked thereon, which form

10 a part of this specification.

This invention relates to improvements in scarfs or neckties, the great consideration in the manufacture of which consists in so arranging and permanently securing together 15 the parts of a scarf as to give to the completed article the semblance of a natural knot or tie. A very large proportion of the users of these articles are unable to take a straight piece of goods, such as an ordinary piece of ribbon or 20 scarf, and form the same about the neck in a nice-looking tie, bow, or other form of knot, and hence these ties have heretofore largely been made by sewing the same permanently in position. In such ready-made scarfs the 25 appearance of the natural puffing and plaiting of the bow or tie is to some extent imitated by means of pasteboard or other filling material inserted beneath the folds of the tie. After 30 a very limited use of these "made-up" scarfs it is found that the plaits and folds flatten and lose their shape, thus destroying all semblance of having been tied by hand.

The object of this invention, therefore, is to produce a scarf part of which shall be permanently made up and part of which shall be 35 loose and adapted to be "made up by hand," and also adapted to be so united with the first-mentioned part as to give the whole the puffed-up and plaited appearance of a scarf made 40 up by hand.

To this end the invention consists in the novel combination herein shown and described, and more particularly pointed out in the appended claims.

45 In said drawings, Figure 1 is a plan view of a scarf embodying my invention. Fig. 2 illustrates the made-up portion of the scarf—to wit, that portion attached to the neckband. Fig. 3 illustrates that portion of the scarf 50 adapted to be "tied by hand." Fig. 4 illus-

trates another form of scarf embodying the invention.

In the illustrations, A is a neckband of the usual pattern, provided at one end with a hook a and at the other end with a loop or eye a', 55 adapted to be engaged by the hook a, whereby the ends of the neckband may be secured together.

B is a loop or puff of material permanently secured to the neckband A. The loop B is 60 in such form as to imitate the loop of an ordinary hand-tied knot when tied with the material of which neckties would usually be made. The loop B is provided with an opening b therethrough.

65 C is a single piece of material, preferably of the same pattern on both its sides, and adapted to be engaged with the loop B by having one of its ends c c inserted in and through the opening b in said loop B. After 70 one of said ends c of the piece C has been passed through the loop B the said ends c c may be brought together and crossed, as shown in Fig. 1. In such case the two parts of the single piece C may be secured together at d 75 by a pin D or other suitable means. The crossing of the ends c, as above explained, will cause plaits or puffs to be formed in said piece C, as clearly shown at c' in Fig. 1, the character or design of which may be altered 80 obviously by bringing the said ends c together in various ways. Such alterations are so obvious to those acquainted with this subject that I do not deem it necessary to illustrate more fully the different uses or modifications of designs into which this scarf may 85 be made. I have, however, illustrated in Fig. 4 one of such modified forms, which is deemed sufficient for the purpose. In such modified form the single piece C may, perhaps, be some- 90 what shorter than that used in forming the scarf illustrated in Fig. 1. In making this form of scarf shown in said Fig. 4 I prefer to double the said piece C and pass the two ends c c through the loop B in the same direction. 95 Other styles of knot may of course be adopted.

It will be obvious that by reason of the piece C being separate from the loop B not only a great variety of forms may be given to the scarf proper, but the worn-out portion of the 100

scarf may be taken up by simply shifting the position of the part C with regard to the part B. This repetition of use may be further extended by making the part C doubled, as hereinbefore explained. By making the parts 5 separate and of washable material it is obvious that the scarf or tie can be readily cleansed by washing, as there is no pasteboard or other lining required.

10 What I claim is—

1. As a new article of manufacture, a convertible scarf consisting of two parts or pieces, one part consisting of a neckband and a permanently-attached transverse loop formed by means of a strip or band sewed at both ends 15 to the neckband, and the other part consisting of a single separate strip of cloth adapted to be inserted through said transverse loop.

2. As a new article of manufacture, a convertible scarf consisting of two parts or pieces, 20 one part consisting of a neckband and a permanently-attached transverse loop formed by means of a strip or band sewed at both ends to the rear or inner surface of the neckband, and the other part consisting of a single separate strip of cloth adapted to be inserted through said transverse loop, substantially 25 as described.

In testimony that I claim the foregoing as my invention I affix my signature in presence 30 of two witnesses.

LINCOLN H. BARTLETT.
